PICK HANDLE PROTECTOR

Ernest Tyler, Daisytown, Pa.

Application December 18, 1940, Serial No. 370,621

1 Claim. (Cl. 306—37)

My present invention relates to a protector especially adapted for use on a pick handle adjacent the head thereof for the purpose of greatly increasing the length of life of such handle.

A conventional pick or pick ax has a metal head 10 which is generally slightly curved in a longitudinal direction and which terminates at each end in a relatively sharp point 11, flaring from each such point to the central heaviest portion 12 thereof. The central portion is provided with a socket 13 for the reception of one end of the handle 14 and is frequently provided with V-shaped projecting portions (eyes) 15 in the conventional manner. The wooden handle employed with such head is subject to battering due to violent contact with material being broken or loosened by means of the pick. Particularly in connection with rocky materials or formations, the handle is subject to countless blows and the abrasive action of such rocky material, with the result that the handles become so damaged after a relatively short time that they must be replaced. Depending on the particular type of work involved, handles must be replaced at rather frequent intervals.

The foregoing situation is relatively unsatisfactory and the constant damaging and replacement of handles is frequently a matter of very serious expense. This often works a hardship where it can be least afforded. Some steps have been taken in the past with a view toward decreasing the frequency with which such handles must be replaced and, to some extent at least, cutting down the damage to such handles by rocks and other hard or abrasive materials. So far as I am aware, however, there is no protector for handles which is available on the market today and I believe that this is not only highly significant as showing that prior proposed protectors were of little or no value but that there is a real need and demand for a satisfactory pick handle protector.

It is, accordingly, one of the objects of my present invention to provide a protector especially adapted for picks and pick axes which will enable the damage to and replacement of handles to be drastically reduced.

Another object of my invention resides in providing handles of the character herein set forth with a protector of such nature that each handle will have a life at least about four times as long as the same handle without my new protector.

Another object resides in providing a protector which, while substantial and long-lived in its na-

ture, can be made and sold at a very nominal cost.

A still further object of the invention resides in cutting down the cost of work or operations which involve the use of picks or pick axes.

Other and further objects and advantages will be understood by those skilled herein or will be apparent or pointed out hereinafter.

In the accompanying drawing wherein I have 10 illustrated a preferred form of the present invention:

Figure 1 shows my protector in operative position on the handle of a pick or pick ax and in the proper relationship with respect to the head 15 thereof;

Fig. 2 illustrates in perspective my new protector fully formed and ready for application to a handle;

Fig. 3 represents a cross-sectional view of the 20 new protector taken on line III—III of Fig. 2;

Fig. 4 illustrates the blank from which the protector is first formed prior to its being shaped to final form as shown in Fig. 2;

Fig. 5 illustrates in fragmentary enlarged section the interlock joint employed in the finished 25 protector;

Fig. 6 is a section taken on the line VI—VI of Fig. 2; and

Fig. 7 is a section taken on the line VII—VII 30 of Fig. 1.

Prior protectors which have been proposed but which have found no commercial use so far as I am aware have generally been made of flimsy material poorly designed. This, in my opinion, 35 is the chief reason for lack of adoption of a pick handle protector which is so sorely needed and yet the demand for which has not heretofore been successfully filled. Proposed protectors have also suffered, I believe, from the fact that they 40 either did not give effective protection or they were too difficult and expensive to manufacture and therefore eliminated themselves from adoption and use since this necessitated elaborate dies and machinery for production purposes.

Still other protectors were supplied in the form 45 of a blank only, which had to be applied and shaped around each individual handle as used. This is not only unsatisfactory except where the protectors are made of very light or thin material but present standardization of handles has 50 eliminated the necessity for such. Jointly and severally, there have therefore been numerous reasons for the present status of protectors of the character here involved.

55 Referring now to the drawing and describing

my new protector in detail, I first produce from a suitable starting piece 16 a blank 17 which tapers from one end toward the other but which at the wider end is provided with a pair of spaced rounded projections terminating in three-sided rectangular lugs or extensions which are substantially tangent to the projections. On its sides, the blank 17 is notched out as shown at 18 and is provided contiguous thereto with longitudinally extending partial marginal portions 19, the dotted lines adjacent the same indicating the points at which the same are folded over for interlocking purposes as hereinafter described. The blank 17 can be produced very simply by cutting the same out with an inexpensive cutter or die.

In accordance with this invention, the material from which the protectors are made is preferably cold rolled steel having a substantial thickness, e. g., of the order of .014-.025". Such material of such thickness is not only hard, resistant and stiff but is well adapted to receive and absorb the shocks and blows which would normally act directly upon the wood of the handle. Such a protector also is capable of receiving a good deal of punishment without breaking or rupturing and without allowing any very considerable damage to be transmitted to the wooden handle therebeneath for a substantial period of use.

As will be understood from reference to Figs. 2 and 3 in particular, the blank 17 of Fig. 4 is shaped or formed so that it assumes a substantially tubular condition having a substantially oval bore to form the protector 20. The cold rolled steel is shaped, after it is cut out, by a forming or shaping machine provided for that purpose, although the configuration may be imparted to the blank in any suitable manner. Not only is the cold rolled steel bent to form an oval or ellipse (note Fig. 3) but the marginal portions 19 already mentioned are folded over to produce interlocking portions 21 which act on each other in the general manner of a shepherd's crook type of connection. The fact that the material in its formed condition is under tension and compression causes the interlocking portions to hold each other firmly and in such manner as to prevent accidental or undesirable disengagement.

The notching of the material adjacent one end of the folded-over portions enables the rearward parts of the protector to be brought into close juxtaposition and, moreover, provides the overlapping partial marginal extensions 22 by means of which the device can be fastened to the pick handle through use of auxiliary fastening elements such as the tacks, screws or brads 23. This arrangement, moreover, forms a protector which has no point of weakness and in which those portions which might normally be expected to be the weak points are at least as strong as and frequently stronger than the remainder of the protector so that the utility and protective function of the device are not rapidly destroyed by contact of such portions with hard or abrasive materials or formations such as rocks or the like. By referring to Figs. 2 and 3 in particular, it will be appreciated that at the joint or line of connection the protector has a minimum of two thicknesses of cold rolled steel and in a large proportion of the length of the joint has four thicknesses of cold rolled steel due to the interlocking structure employed.

Further attention is directed to the three-sided

lugs 24 previously referred to in connection with blank 17. In Figs. 2 and 6 it will be particularly noted that these lugs have been also folded over and that they are converted to a generally arcuate form substantially complementary to the adjacent portions of the protector. It will be appreciated that when the blank of Fig. 4 is formed to the device of Fig. 2 the corresponding end of the completed device now has a bifurcated character and that the space between the furcations is V-shaped, diminishing to zero at one end of the interlocking parts. Each projecting portion 25 of the V is in a concavo-convex form and substantially U-shaped in cross section, as will be clearly apparent from Fig. 6.

The lugs 24 in their ultimate configuration also have a dual function. Due to the fact that the folding over of these lugs presents a smooth rounded forward edge the ease of applying the protector to a handle is greatly increased since this smooth edge guides the protector along the handle in such a manner as to prevent catching or sticking, and when the protector is in its ultimate position, as shown in Fig. 1, the distal ends 26 of such lugs form relatively sharp wedge-like members which dig into the wood of the handle a small but sufficient amount to prevent relative movement of the protector on the handle. The V-shaped end of the protector is also so designed and constructed as to cause the forward end of the protector to be spread or wedged open since the usual handle generally flares somewhat toward the head of the pick. This is taken advantage of in connection with my present invention to give at least two additional points of advantage and utility. The spreading of the V-shaped termini on the forward end of the protector causes the interlocking portions to grip each other tighter and tighter until a practically immobilized connection is produced in the final position of the protector on the handle. In addition to this, as the forward V-shaped end of the protector spreads, the rearward tapered end correspondingly contracts so that by the time the protector is in its final position the rearward end of the protector has taken a firm unyielding hold on the handle. Thus the protector is so firmly positioned that in many cases no auxiliary fastening means at all are required. I prefer, however, to put small tacks or brads in the positions shown in Fig. 1 and designated by the numeral 23 in such manner that they pass through both layers 22 of the cold rolled steel, as will be clearly understood from a consideration of Fig. 7. I may also apply such fastening instrumentalities to the sides of the protector at points indicated by the arrows 26 of Fig. 1.

It will be appreciated from the foregoing that I have for the first time provided a substantial and practical protector which very greatly increases the life of pick or pick ax handles and which can not only be made at a nominal cost but which can be fully formed ready for use in such manner that they need merely be slid over the handles to take their final position. Likewise the protectors may be very simply and quickly removed merely by removing or prying out the tacks or brads and unlocking the interlocking parts. Then a new protector can be positioned to replace the old and the same handle thereby continued in use for another extended period. Not only do I make it possible to effect material savings over a period of time but I make it unnecessary to lay in a stock of extra handles and to insert and fasten such handles in place in the

conventional manner. The protector in no way detracts from the use thereof and, in fact, improves the appearance and increases the effectiveness of the use of such pick, as has been definitely proved by actual use. The hard and tough nature of the cold rolled steel forms an unusually effective article.

It is further to be understood that the foregoing is intended as illustrative and not as limitative and that within the spirit and terms of the 10 appended claim I may make various additions, omissions, substitutions and modifications without departing from the principles and scope hereof.

Having thus described my invention, what I 15 claim as new and desire to secure by Letters Patent is:

A cold rolled steel protector for a pick handle which comprises a tapering tubular shield of oval section which is preformed to fit such handle and which is adapted to be slid thereover in fully 5 formed condition larger end foremost, said shield having one V-shaped end capable of interfitting with said pick head and a pair of terminal in-turned lugs at the ends of such V adapted to engage said pick handle close to said pick head, said protector having a seam extending for a substantial proportion of the length of the protector along one side which includes complementary interlocking bent marginal members and at least one marginal extension between which and the adjacent portion of the interlock the protector is notched out.

ERNEST TYLER.
